MATRIX FOR CASTING ELEMENTS OF PRINTING-FORMS.

1,307,676.

Specification of Letters Patent. Patented June 24, 1919.

Original application filed February 15, 1918, Serial No. 217,363. Divided and this application filed March 25, 1919. Serial No. 284,995.

To all whom it may concern:

Be it known that I, AMOS L. KNIGHT, a citizen of the United States, and a resident of Philadelphia, in the county of Philadelphia and State of Pennsylvania, have invented a certain new and Improved Matrix for Casting Elements of Printing-Forms; and I do hereby declare the following to be a full, clear, and exact description of the 10 same, reference being had to the accompanying drawings, forming part of this specification, this application being a division of my application Serial Number 217,363, filed February 15, 1918.

15 The invention relates to matrices for casting strip material such as rules, leads and the like, such matrices being adapted to be used in conjunction with a mold to give form to the printing face or equivalent part of the strip material produced by the associated 20 mold and matrix. More particularly the invention relates to matrices for molds of the type disclosed, for example, in United States Letters Patent Number 1,222,415, dated 25 April 10, 1917, and adapted as part of a type casting machine to produce printers' rules, leads and the like, in fused sections or increments to form strips of indefinite 30 length or in non-fused sections of predetermined length.

The patented apparatus, generally speaking, comprises a mold having an opening for the entrance of molten metal and being open at one end for the exit of the congealed metal, means for feeding forwardly the congealed metal, and means for forcing molten metal behind the forwardly fed congealed metal. The operations of casting and feeding are carried on in timed relation to each other and are repeated in accordance with the amount of product desired. For feeding the congealed metal a reciprocatory mold blade is shown in the said patent, which 40 blade advances, when the metal in the mold cavity is congealed, to push said metal forwardly toward the exit opening of the mold, and retreats thereafter to leave a cavity for the reception of the molten metal to form 45 the succeeding cast.

The present invention has among its principal objects to produce strip material mat-

rices consisting of a plurality of selected parts arranged in such manner as to insure marked advantages of the nature hereinafter referred to. Such matrices are preferably made by a method which permits of the forming, as by punching, of a blank matrix into what may be termed a formed blank matrix provided with one or more cavities or depressions having the general characteristics of the cavity or cavities desired in the finished matrix, the punching operation being followed by a severing or cutting of the formed blank matrix through one or more of the cavities, the severing for each cavity being on a plane chosen to dimension the cavity and especially the printing surface forming face in accordance with the dimensions desired in the finished matrix; the severing operation being followed by the substitution for the cut away portion of the side matrix member, preferably permanently secured, as by rivets, to the main matrix member and serving to form the wall of the cavity along the plane of severance. A single punch of maximum strength is preferably employed and a stock of formed blank matrices is thus produced from which stock a variety of finished matrices may be made, when desired. Another object of the invention is the production of a matrix having a cavity one wall of which, as the wall formed by the side member, may be perpendicular to the bottom or printing surface forming face, of the cavity, whereby a type-metal printer's rule may be produced having a straight side continued up to the printing surface, known as a "flush side" rule.

Another object is concerned with the production of a matrix having a plurality of parallel cavities from which a rule for printing, for example, a plurality of parallel lines may be produced. Such a rule is provided with parallel printing surfaces having a groove or counter between them. If the counter is not sufficiently deep it will receive and retain ink in the printing process and the parallel printed lines produced will then frequently be blurred or otherwise imperfect. The matrix of this invention of the kind provided with a plurality of parallel cavities has a maximum total width of cav-

ity bottom coupled with a high elevation or bead between adjacent cavity bottoms, a structure from which results a maximum total printing width in the rule produced from the matrix coupled with a deep counter in the rule between adjacent printing surfaces. The matrix structure as well as the process of making the matrix will now be more fully set forth in connection with the following description of the invention as illustrated in the accompanying drawings, in which

Fig. 1 is a sectional view of a mold for typemetal strip material, the section being substantially in the plane of the mold blade.

Fig. 2 is a cross section of the mold, the section passing through the nozzle opening and also through parts of the pressure screw clamping device.

Fig. 3 is a perspective view of the matrix.

Fig. 4 is a sectional diagrammatic view illustrative of part of the method of forming the matrix.

Fig. 5 is a cross section of the formed blank and indicates by a broken line a possible severing plane.

Fig. 6 is a cross section of the finished matrix including a side member riveted to the main member on the plane of severance of the formed matrix blank indicated in Fig. 5.

Fig. 7 is a fragmentary perspective view of a printer's rule formed by the matrix of Fig. 6, and

Fig. 8 is a cross section of a matrix similar to that of Fig. 6 but having parallel printing surface forming faces of different total width and also having two separate side pieces instead of one.

Inasmuch as apparatus substantially corresponding to that of the patent hereinbefore mentioned has gone into extensive public use and is well understood in the art, it is thought to be unnecessary to illustrate herein operating mechanism or stops for the mold blade and means whereby the molten metal is injected into the mold cavity, nor is it necessary, for an understanding of the present improvement, to illustrate in detail means for severing the gate from the side of the strip, especially as operating mechanism and the metal melting and injecting mechanism may substantially correspond to mechanism found in the type casting machines manufactured by the Lanston Mono-type Machine Company, which have been in extensive public use for many years.

Referring to the accompanying drawings, it will be seen that the mold illustrated in Figs. 1 and 2 embodies a mold base block 3, which is formed with a channel therethrough in the direction of movement of the mold blade, thus providing front and rear upwardly extending portions 4 which are adapted to be connected across the top of

the mold by a tie bar or bars 5. Confined within the channel extending through the mold base are the type or side blocks between which the cavity for the reception of the molten metal is formed, and these type or side blocks are preferably in the form of bars which extend beyond the mold cavity in each direction and are adapted to be separated a distance which will determine the width of the mold cavity and consequently the point size of the element being cast. The rear type or side block 8 (Fig. 2) is preferably formed with a smooth inner face and constitutes one wall of the mold cavity as well as the wall of the passage in which the mold blade works and of the exit opening in which the congealed metal is retained during the injection of molten metal to form a succeeding cast. The front type or side block may be of similar construction and arranged to be placed in opposition to the block 8 but it is preferably formed in two sections 9 and 10, for convenience of manufacture, inasmuch as it has been found desirable to provide at one side of the mold cavity a channel and exit opening through which air and a portion of the molten metal from the mold cavity may escape in the form of a more or less spongy mass, which, for convenience, may be called a gate lying at one side of the element and adapted to be severed therefrom.

By reference to Fig. 2 it will be seen that between the two sections 9 and 10 there is formed a narrow space which widens out within the type block in the form of a channel which is conveniently of a dove-tail or triangular cross section, as indicated at 12. The channel 12 and the narrow entrance slot which connects the channel with the mold cavity are preferably slightly tapered or of increasing cross section toward the exit end so as to prevent binding during the movement of the gate toward the exit of the channel. Where the front type block is made in two sections, as just described, the upper section 9 is preferably made rigid with the lower section 10 by being fixed accurately thereto and supported by an upwardly extending portion 10^a of the section 10, to which it is connected by screws or other suitable fastenings, as shown clearly in Fig. 2.

The two type blocks forming between them the mold cavity and mold blade channel are positioned laterally of the mold base by a packing plate 17 placed back of the rear type block and by the pressure screw 18 passing through the front projection 4 of the mold base and adapted to operate against the front type block. This pressure screw, in the preferred construction, is operated periodically in time with the feeding of the element being cast so as to clamp the walls of the mold cavity together dur-

ing the casting operation and to release such pressure during the feed of the element forwardly in the mold cavity.

The bottom of the mold cavity is formed 5 by the mold base and is provided with a nozzle opening 20 through which the molten metal is injected into the mold cavity through a nozzle 20^a indicated in dotted lines in Fig. 1.

10. In the specific embodiment of the invention illustrated herein the mold is adapted for the making of printers' type-high strip material provided with a printing surface, the latter and the portion of the strip in 15 proximity to said surface being formed by the matrix 21. This matrix, as shown, is provided with a cavity the bottom of which constitutes a narrow printing surface forming face 22, and a wide printing surface 20 forming face 22^a separated by an elevation or bead 22^b, being designed to make a printer's rule with parallel light and heavy printing edges separated by a counter as shown in Fig. 7. The matrix recess extends 25 through one end of the matrix to its full depth so as to allow of the endwise ejection of the rule cast against the matrix; the other end of the cavity stops short of the end of the matrix whereby an unpunched end portion 21^c (Fig. 1) is provided for sliding 30 contact with the mold blade. The matrix when positioned rests upon the type blocks and is adapted to seat against a matrix abutment 23 mounted on the upper face of 35 the rear type block; it is held firmly in position by a matrix clamp 25 having two surfaces 25^a for coöperation with one edge and the top of the matrix and inclined surface 25^b for coöperation with a corresponding inclined surface on the matrix abutment 23, whereby when the matrix clamp is forced 40 down by its clamping screw 26 the matrix will be forced downwardly and against its abutment where it will be held with precision and in such relation to the type block as to prevent any liability of molten metal 45 escaping through the joints. A squirt preventing shield 40 may, if desired, be removably held upon the clamp 25 by the washer 50 41 yieldingly pressed against the shield by the spring 42 positioned between the washer and the head of the screw 26.

The mold blade 27 which is mounted to reciprocate between the side blocks is of a 55 thickness which corresponds to the point size of the material being cast and it is guided by the side blocks, and by the guide extensions 31, 32, the forward and rearward limits of its movement being determined by 60 suitable stops, not shown. The mold blade is provided with means whereby its operating member 35 may be readily attached thereto, such means conveniently and preferably consisting of a centrally located circular bearing into which a journal stud 36

on the end of the member 35 is adapted to work. Immediately forward of this circular bearing the mold blade is formed with an aperture 28^a preferably rectangular for the reception of a lateral rectangular projection formed on the rear end of the gate pusher 28. The projection of the gate pusher fits loosely within the aperture in the mold blade so that the pusher may without binding adapt itself vertically as may be required by the guide channel 12; the parts are rectangular so that in any position a large bearing surface is provided.

In accordance with the preferable method of making the matrix of this invention, a 80 matrix blank is placed in a container 43 and operated upon in the usual fashion by a punch 44, the latter having projections and depressions corresponding respectively with the depressions and projections desired in 85 the formed matrix blank 45. The projections of the punch, or certain of them, are larger and stronger than required for producing a particular finished matrix; for example, the punch projection 44^a is wider 90 than the corresponding depression or printing surface forming face desired in the matrix shown in Fig. 6 and the matrix blank 45 is thereafter cut away on a plane corresponding with the desired width of the 95 printing surface forming face in the finished matrix, *i. e.*, the plane indicated by the broken line X, (Fig. 5). The side of the cavity is formed by a side matrix member 21^a (Fig. 6) the width of which added to the 100 width of the main matrix member is preferably equal to the desired width of the finished matrix. The side and main portions of the matrix are secured together 105 as by rivets 21^b.

Among the advantages of this method of manufacture may be pointed out the following:—A large stock of formed matrix blanks 45 may be produced by punching matrix blanks, with a single punch from which stock a variety of finished matrices may be made by cutting away in different planes to form matrices for wide and narrow printing faces. The provision of a wider punch projection 44^a than may be desired for the 110 corresponding cavity in the finished matrix renders the punch 44 stronger than if it were made of the dimensions desired for the finished matrix and it may have counter-balancing inclines regardless of the width 115 of the cavity in the finished matrix, and there is thus less liability of breakage. The punch depression forming the bead 22^b of the finished matrix, may be made deeper than would otherwise be practical so as to 120 produce a higher bead 22^b in the finished matrix; and consequently a deeper counter 125 element 46^a in a given point size rule or other element 46 produced from said matrix. This advantage is of great practical importance 130

in connection with the manufacture of matrices for type metal elements having a narrow counter because with the deep counter resultant from this process the collection of ink therein during the printing operation and the blurred and otherwise imperfect printing matter produced because of such collection are practically prevented. Another advantage inherent in this invention 10 is that a product such as that shown in Fig. 7 is obtainable one or more sides of which extend in a single plane up to the printing surface. This is due to the use of a side member 21^a which has no bevel of the 15 surface forming the side wall of the depression 22^a; said side wall, being perpendicular to the printing surface forming face of the depression 22^a, is, in effect, a continuation of the mold wall and the product 46 shown in Fig. 7 shows no break or change 20 of direction in the surface formed by the mold and the alined surface formed by the side matrix member 21^a. A product of this kind is particularly desirable, as will readily 25 be understood by those skilled in the art, when it is necessary to produce an accurate joining of design in printed matter and such design is partly on one typemetal element and partly on an adjoining element. 30 A further advantage of the invention lies in the fact that the beveled or slanting walls of the punch may be beveled at the proper angle for giving requisite strength and producing smooth surfaces in the formed matrix 35 blank, although such angle may not be the most desirable in the finished matrix, for, by cutting away and replacing by one or more side pieces a matrix may be produced having the proper bevel from the viewpoint 40 of the matrix and its use, or may indeed have no bevel at all, and is free of many of the defects resultant from the usual methods of manufacture.

In Fig. 8 I have shown one of the above 45 mentioned modifications in which the matrix blank 21' formed by a punch to contain two wide printing surface forming faces 22^a and 22^c separated by the bead 22^b is subsequently severed through both of these faces and the 50 side piece 21^a and the second side piece 21^d applied, the whole being preferably riveted together by the rivets 21^b.

By eliminating the side bevel from the 55 matrix a rule having a straight side is obtained, the printing surface of which extends laterally to the side wall of the rule body. This is particularly advantageous in connection with rules having a plurality of parallel printing surfaces with counters 60 between them, because one or more of these surfaces may be thus extended to the side wall of the rule so as to gain a greater width

of printing surface therefor or to cause adjacent printing surfaces of given widths to be spaced apart to a maximum degree with 65 a thin body whereby a sufficient space is left between them to provide a deep counter in the rule. It will thus be seen that the matrix of the present invention is provided with a maximum total width of cavity bottom, the cavity bottoms corresponding, of course, with the printing surfaces of the rules produced from the matrices and with a high elevation or bead between bottoms. This permits of a maximum total width of 70 printing surface in any given point size rule and of desirably deep counters in rules 75 provided with a plurality of parallel closely spaced printing surfaces.

In operation the mold blade is reciprocated 80 from a point in advance of the nozzle opening 20 to a point in rear thereof, the top of the blade being in sliding leak-proof contact with the surface 21^c of the matrix 21 and molten metal is injected through said 85 nozzle opening when the blade is in its retracted position.

The forward wall of the mold cavity is not a structural part of the mold and is not shown; it is formed by the rear edge of the 90 typemetal cast previously made and thereafter advanced by the forward reciprocation of the blade. At the time of casting, as will readily be understood by those familiar with the art, this previously cast type metal 95 is clamped tightly by the screw 18 in position to withstand the pressure of the entering molten metal. By removing the shield 40 then unscrewing the screw 26 and lifting off the clamp 25, the matrix can be 100 readily removed and replaced.

What is claimed is:

1. A matrix for casting printing form elements having a printing face coextensive with and unbroken in the direction of the 105 length of the element, consisting of a matrix body having a matrix cavity therein with an elongated printing surface forming face, said cavity being open at one end to the full depth of the cavity and having a side wall 110 which is perpendicular to the printing surface forming face and extending to the full depth of the cavity.

2. A matrix for casting fused increment printers' strip material, consisting of a plurality of selected parts combined to form 115 a matrix cavity having a bottom for forming the face of the strip material, the sides and one end of said cavity being closed and the other end thereof open for the exit of 120 said material, one of said parts constituting a side wall of the cavity, said wall being perpendicular to the bottom of said cavity.

AMOS L. KNIGHT.
